OIL-ENGINE.

1,128,108.

Specification of Letters Patent.

Patented Feb. 9, 1915.

Application filed May 17, 1910. Serial No. 561,794.

To all whom it may concern:

Be it known that I, JAMES WILLIAM CROSS, a subject of the King of Great Britain, and resident of London, England, have 5 made a new and useful Improvement in Oil-Engines, of which the following is a specification.

This invention relates to oil engines of the kind in which the oil serving as fuel is 10 introduced into the combustion chamber at the end of the compression stroke, and wherein after ignition has taken place, a further volume of compressed air is intermingled so as to insure complete combustion 15 of the fuel. In engines of this class, when the power is required to be reduced, the amount of oil which is supplied to the combustion chamber at each stroke is correspondingly limited. It is, however, impracticable to reduce the oil supply below a certain limit because the mixture would become too weak to ignite. The range of power developed by the engine is therefore unduly restricted. According to the present 20 invention, in order to obviate this defect, the combustion chamber is formed in two or more parts, each of which is provided with an independent oil supply and in each of which independent ignition takes 25 place. By this means the total oil supply to the engine can be reduced by cutting off the supply from one or more of the parts of the combustion chamber without interfering with the proper ignition of the fuel 30 in the other parts of the combustion chamber which are supplied with the customary amount. The variation in the oil supply may be effected either manually or automatically by means of a suitable governor 35 as desired.

In order that the invention may be clearly understood, an example of how it may be carried out in practice will now be described with reference to the accompanying drawing the single figure of which is a view in sectional elevation of a portion of an oil engine showing the invention applied thereto.

The valve mechanism of the engine comprises an air inlet valve 1 arranged adjacent to the end of the cylinder 2 of the engine, an exhaust valve 3, air valves 4 and 5 arranged at the top of the combustion cham-

ber 6 which is a well defined extension of the cylinder 2 and is in free communication therewith by means of a passage 7.

The combustion chamber 6 is shown divided into two portions 8 and 9 by means of a partition 10 attached to the inner wall of the combustion chamber and projecting outwardly into the passage 7. Fuel valves 11 and 12 are provided adapted to project the fuel into the compartments 8 and 9 of the combustion chamber at the end of the compression stroke. These valves may be 65 of any well known construction and can be arranged to inject the fuel either in a liquid or in a vaporized state.

The air inlet valve 1 and the air inlet valves 4 and 5 are of well known construction and are operated by any suitable type of mechanism in a well known manner. As here shown, the air valve 1 is normally retained on its seat under the action of a spring 13 interposed between webs 14 attached to the casing in which the valve is located and a collar 15 secured to the stem of the said valve. The auxiliary air valves 4 and 5 are provided with similar springs 16 and 17 respectively which normally retain the valves upon their seats.

The cylinder of the engine is shown provided with the usual water jacket 18 and with passages 19 for liquid circulation arranged adjacent to those parts which are 85 liable to become over-heated.

The ignition of the fuel may be accomplished by any suitable or well known ignition devices or the compression of the air and high temperature of the combustion chamber may be relied upon for producing ignition.

In the arrangement here shown, the combustion chamber is divided into two compartments so that when the power is required to be reduced, the amount of oil supplied to one compartment only will be varied until the oil supplied to that compartment has reached a point when to further reduce the supply of oil to that compartment, the mixture would become too weak to ignite. Further reduction in the power required will be effected by correspondingly reducing the amount of oil supplied to the other compartment and by this means a variation in the power exerted by

the engine may be obtained within wide limits.

It will be understood that the oil supply may be varied either manually or automatically and means for effecting such variation manually are illustrated diagrammatically at 20. In cases in which a very wide variation in the power exerted by the engine is desirable, the combustion chamber may be 10 divided into a greater number of compartments, a separate oil supply valve being provided in each compartment.

From an inspection of the drawing it will be apparent that if the oil supply to one 15 compartment is cut off entirely the explosion will occur in the other compartment and effect the desired outward movement of the piston with a corresponding reduction in power.

20 From the foregoing description it will be clear that the total amount of oil supplied can be reduced much below that which it would be necessary to supply if at all times the whole of the combustion chamber were 25 utilized to form a gaseous mixture, the presence of air in one compartment of the combustion chamber to which the supply of liquid fuel has been cut off in no way affecting the explosion in the other compartment or compartments to which liquid fuel 30 is being supplied. The engine is therefore much more flexible and the range of power which it can develop is much greater than is the case with engines of the ordinary 35 construction.

It will be understood that the invention is not limited to the particular construction and arrangement of the valves herein described and illustrated and various modifications may be made without exceeding the 40 scope thereof, for instance, the invention can be applied to oil engines working on a two-stroke, four-stroke or other cycle and having any desired number of cylinders.

45 What I claim is—

1. The combination in an oil engine of a combustion chamber divided into a plurality of continuously connected compartments and means for varying the supply of combustible fuel to each compartment.

50 2. The combination in an oil engine of a combustion chamber divided into a plurality of continuously connected compartments and means for independently varying the supply of combustible fuel to each compartment.

55 3. The combination in an oil engine of a combustion chamber divided into a plurality of continuously connected symmetrically arranged compartments and means for varying the amount of combustible fuel supplied to each compartment.

60 4. The combination in an oil engine, of a combustion chamber divided into a plurality of continuously connected symmetrically ar-

ranged compartments and means for independently varying the amount of combustible fuel supplied to each compartment.

5. The combination in an oil engine, of a combustion chamber divided into a plurality of continuously connected compartments and means for supplying combustible fuel to each of said compartments in accordance with the load. 70

6. The combination in an oil engine, of a combustion chamber divided into a plurality of continuously connected compartments and means for independently varying the amount of combustible fuel supplied to each compartment in accordance with the load. 75

7. The combination in an oil engine, of a combustion chamber divided into a plurality of continuously connected compartments, means for independently varying the amount of combustible fuel supplied to each compartment, and means common to all compartments for igniting the explosive mixture admitted to the combustion chamber. 80

8. The combination in an oil engine, of a combustion chamber divided into a plurality of continuously connected compartments, a separate fuel injection device located in each compartment and means for independently varying the amount of combustible fuel supplied to each compartment. 90

9. The combination in an oil engine, of a combustion chamber divided into a plurality of continuously connected compartments, a separate fuel injection device located in each compartment, an air inlet valve supplying air to the engine cylinder through the combustion chamber and means for varying the amount of combustible supplied to each compartment. 95

10. The combination in an oil engine, of a combustion chamber divided into a plurality of continuously connected compartments each of which is in free communication with the cylinder of the engine, an air inlet valve for admitting air to each compartment and an air inlet valve supplying air directly into the cylinder. 105

11. The combination in an oil engine, of a combustion chamber divided into a plurality of continuously connected compartments, separate inlets for the combustible fuel located in each compartment, air inlet valves for admitting air through said compartment to the cylinder and means for varying the amount of combustible supplied to each compartment. 115

12. The combination in an oil engine, of a combustion chamber divided into a plurality of continuously connected compartments, an injection device for the combustible fuel located in each compartment, a separate air inlet valve for each compartment and an air inlet valve for supplying air directly into the cylinder. 125

13. In combination with a cylinder of an 130

internal combustion engine, a combustion chamber divided into a plurality of combustion compartments, each of which is in open and continuous communication with the engine cylinder.

14. In combination with the cylinder and piston of an internal combustion engine, a combustion chamber located in the cylinder head of the engine and divided into a plurality of combustion compartments, each of which is in open and continuous communication with the engine cylinder and forms a pocket partially segregated by the piston when the piston is at the end of its compression stroke.
15. In combination with the cylinder and

piston of an internal combustion engine, a combustion chamber located at the compression end of the cylinder and divided into compartments by means of a partition 20 extending parallel to the line of motion of the piston, each of said compartments being in continuous and open communication with the engine cylinder.

In testimony whereof I have hereunto subscribed my name this twenty-eighth day of April, 1910.

JAMES WILLIAM CROSS.
